(57) **CLAIM**

The ornamental design for a watch bracelet as shown and described.

DESCRIPTION

FIG. 1 is a top view of a watch bracelet of my present design;

FIG. 2 is a bottom view thereof;

FIG. 3 is a left side view thereof;

FIG. 4 is a right side view thereof;

FIG. 5 is a rear view thereof;

FIG. 6 is a front view thereof;

FIG. 7 is a top right perspective view thereof; and,

FIG. 8 is a bottom right perspective view thereof.

The broken lines in the drawings represent portions of the watch bracelet and form no part of the claimed design.
